UNITED STATES PATENT OFFICE.

EDWARD ALFRED GRAHAM, OF BROCKLEY, ENGLAND; MARIA GRAHAM AND ALFRED GRAHAM EXECUTRIX AND EXECUTOR OF SAID EDWARD ALFRED GRAHAM, DECEASED.

TELEPHONIC RECEIVER.

Application filed May 31, 1924, Serial No. 717,063, and in Great Britain June 14, 1923.

In telephone receivers in which a diaphragm is caused to vibrate for the purpose of sound emission or origination of sound waves by electro-magnetic means, it is customary firmly to clamp the diaphragm at its peripheral edge portion between two metal plates or flanges, with or without the interposition of washers of hard rubber, fibre, or other material of similar character, in order to ensure, as far as possible, an equable and comparatively rigid clamp with a view to preventing "chatter" when close adjustment is made of the electro-magnetic system relative to the diaphragm, or, in some instances, to an armature to which the diaphragm is attached.

In a general way it is of course known that a diaphragm may be retained, held, suspended or maintained in position in such a manner as to avoid the setting up therein of an initial strain or stress which otherwise imparts a certain frequency of vibration to the diaphragm when the latter is in use, or accentuates the inherent natural frequency of the diaphragm. It would not, however, be sufficient in the case of diaphragms of telephonic receivers of the type known as loud speakers, to which the present invention particularly relates, to provide for this without ensuring that the initial adjustment of the diaphragm shall remain stable, and the object of the present invention is to maintain the requisite stability.

To this end, the invention consists in arranging that the diaphragm shall be marginally supported at the side next to the electro-magnetic influencing system in a definitely limited manner whilst acted upon at the opposite side by means of a comparatively yielding or elastic character. In this way the diaphragm is electro-magnetically attracted towards and against a substantially rigid bed or seating, but is only elastically held, supported or retained at the opposite side by means against which the diaphragm could be mechanically displaced with relative ease.

The carrying out of the invention may be effected in various ways by employment of gaskets, resilient spring and like devices which in themselves are broadly known and form no part of the present invention, otherwise than in their arrangement and combination for the purpose set forth, as will be

ascertained from the fuller description now about to be given.

In the accompanying drawings, Figs. 1 to 5 inclusive illustrate various ways of carrying the invention into practice. Figs. 1^a and 1^b show respectively in side view and plan part of a bearing ring with a spring finger thereon used in the arrangement shown in Fig. 1. Fig. 2^a shows in side view, part of a bearing ring with spring fingers used in the arrangement shown in Fig. 2. Fig. 4^a shows part of a bearing ring with spring fingers used in the arrangement shown in Fig. 4. Figs. 5^a and 5^b show part of a ring with alternative forms of spring fingers for use in the arrangement shown in Fig. 5.

According to the construction shown in Figs. 1, 1^a, 1^b the casing *a* of the telephonic receiver is provided at its front end with an external flange *b* and formed with an internal recess *c* in which is inserted a diaphragm *d*, embraced on opposite sides of its peripheral portion by a solid ring of rubber, felt, cloth or like sound deadening or damping material (hereinafter referred to for distinction, as the rubber ring), which is of the channel shape in cross section. To the flanged end of the casing is secured, it may be by screws, an end plate or cover *f* having a central sound emission outlet *f*¹ and adapted to bear upon the flange *b*.

The rubber ring *e* rests at its inner side, namely that facing towards the magnetic system within the receiver, on the ledge *c*¹ formed by the recess *c* in the casing *a* and is lightly pressed upon and supported on its opposite side, by a metal or other ring *k* (hereinafter called the bearing ring) having a number of spring fingers *k*¹, say three, extending radially inwards towards the central sound outlet *f*¹ of the cover *f* and bearing against the inner side of the said cover. These fingers may lie in shallow grooves or recesses *f*² formed in the cover. The said rubber ring *e* may, as shown, be of greater radial width than the recess *c*, so that it is supported over only a portion of its radial width.

The bearing ring *k* may be arranged to bear lightly upon the rubber ring *e* embracing the edge portion of the diaphragm *d* by slight pressure applied directly to it in a downward or backward direction by means arranged directly between the bearing ring

k and the cover. Figs. 2 and 2^a show an arrangement of this kind wherein a bearing ring *k* is provided with a number of spring fingers *k*¹, say three, that extend directly upward or outward therefrom and bear against the cover *f* so that the pressure exerted upon or against the bearing ring *k* is applied directly downwards or backwards and applied lightly to the rubber ring *e* and the peripheral edge portion of the diaphragm *d* held thereby. The rear side of the cover *f* may be formed with a channel *f*³ to accommodate the spring fingers. When the bearing ring *k* is of metal or like elastic material, the spring fingers *k*¹ may conveniently be struck upward or outward therefrom, as in the example now being described. Or the spring fingers may each be fixed, as by rivetting, at one end, to the bearing ring, or it may be to the cover *f*, as may be the more convenient.

Or in lieu of spring fingers, elastic bow shaped members *k*² may, as shown in Fig. 3, be attached to the cover *f*, as by rivets *k*³, and act against the bearing ring *k*; or they may be fixed to the bearing ring *k* and bear against the cover *f*.

The elastic bow shaped member *k*² (Fig. 3) when fixed to the cover *f*, may bear directly on the rubber ring *e*, the bearing ring *k* being then dispensed with.

Figs. 4 and 4^a show an arrangement similar to Figs. 2 and 2^a except that the bearing ring *k* with spring fingers *k*¹ is reversed in position, the ring being accommodated in an annular recess *f*⁴ in the cover *f* and the spring fingers *k*¹ bearing directly upon the rubber ring *e*.

According to a further modified construction, the rear side of the cover *f* may be recessed directly above or in front of the bearing ring *k* and a suitable number of rubber balls or pads, or coiled metal springs, or the like, be inserted and arranged to bear directly upon or against the bearing ring and press the same lightly against the rubber ring *e*. The bearing ring in this case may be plain.

Figs. 5 and 5^a show a further modification wherein the peripheral portion of the diaphragm *d* is lightly held against a ring *e*² of soft flexible material such as cloth, rubber or the like by light spring pressure, due for instance to that of a number of spring fingers *k*¹ carried by a ring *k* housed in a groove *f*⁵ in the cover *f*. The spring fingers may be plain as shown in Fig. 5^a and bear directly against the diaphragm, as shown in Fig. 5, or they may each be provided with a small tip *k*³ of felt or like soft material, as shown in Fig. 5^b, to bear directly against the diaphragm.

In some cases, the outer peripheral portion of the diaphragm may be lightly held by spring devices, such as the fingers shown in Fig. 5 or Fig. 5^b, directly against the annular seat *c* in the casing *a* and the annular

seating *e*, or *e*² of rubber, felt or like material be dispensed with without departing from the essential feature of the invention. A greater advantage is however obtained by using a rubber or like seating.

The cover may be secured to the casing of the telephonic receiver in any convenient way, as by screws *m*.

Telephonic receivers embodying the invention can be constructed in various ways without departing from the essential features of such invention. Thus, it is to be understood that the expression "cover" hereinbefore used, means that portion of the casing above or in front of the diaphragm affording acoustic outlet, to which an acoustic amplifier or trumpet is usually applied. Generally, the "cover" providing the acoustic outlet is made readily removable, as by the use of screws, as in the examples shown, but in some constructions, the acoustic outlet *f*⁴ may be formed in one piece with the casing *a* itself, and the diaphragm with rubber ring *e* and associated parts, if any, be introduced from the underside or rear side of the casing and be held in position by suitable retaining means, the electro-magnetic portion of the telephone receiver being afterwards fitted within the casing, or be carried by or upon a separate base to which the casing is secured. The retaining means may conveniently consist of cylindrical lining detachably fixed within the casing *a*, and adapted to form therewith the recess *c* for the rubber ring *e* and diaphragm *d*, with associated parts, if any.

Although the arrangements herein disclosed for supporting or maintaining the diaphragm in position are described with particular reference to a form of telephonic receiver, such as described in the specification of my British Letters Patent No. 15369 of 1915, it will be readily understood the same means may be applied to the mounting of diaphragms of large dimensions which may not involve the necessity of employing an end plate or cover with central opening, but simply a ring of metal or other material forming an abutment, to retain the said diaphragm in position. In this case the supporting members would be adapted to accommodate the means of diaphragmic mounting herein disclosed. Further, the said means may be adapted to the diaphragmic mounting of a telephonic receiver in which the diaphragm is not directly influenced by an electro-magnetic system but is caused to vibrate by or through the medium of a lever, which is provided with an armature subject to electro-magnetic influences, for example, such as described in the specification of my British Letters Patent No. 25112 of 1909. In fact, the method of diaphragmic mounting hereinbefore described may be applied to the diaphragm

member in any form of telephonic instrument.

By employing constructions such as described, the diaphragm will be retained in position without any strain or stress being imparted thereto other than that imposed by the electro-magnetic system, and when influenced by variations in such system, an appreciable advantage, as regards volume, clarity and tonal quality of the sound reproduced, will be apparent, compared with that obtained with the constructions of diaphragm mountings heretofore employed.

By the term "outer abutment" used in the appended claims, is meant, the end cover *f*, or the end wall of the receiver casing *a*, or equivalent device carried by the casing and serving in each case as a rigid or substantially rigid support against which can bear the yielding spring means used to press the peripheral portion of the diaphragm *d* against the stationary solid ring *e*, or an annular seat *c* carried by the casing at the inner side of the diaphragm and serving as an inner abutment for the peripheral portion of the diaphragm. It is to be understood that the solid ring *e* of rubber, felt cloth or like sound deadening or damping material does not act as a spring seat or support, but as a substantially rigid seat or support for the diaphragm *d*, like the hard seat *c*, but its use is preferred, as it forms a sound deadening means to prevent chatter of the diaphragm that might occur if the diaphragm be arranged to bear directly against the hard seat *c*.

Having now particularly described and ascertained the nature of my said invention and in what manner the same is to be performed I declare that what I claim is:—

1. A telephonic receiver comprising a casing provided with a seat, an electro-magnetic diaphragm influencing system within said casing, a diaphragm extending over said diaphragm influencing system and supported by said seat, substantially rigid damping material arranged between said seat and the peripheral portion of said diaphragm and against which the latter bears, an outer abutment and spring means arranged between the outer side of the peripheral portion of the diaphragm and said outer abutment and adapted to exert a yielding pressure against said diaphragm.

2. A telephonic receiver comprising a casing provided with a seat and an outer abutment, an electro-magnetic diaphragm influencing system arranged within said casing, a diaphragm extending over said diaphragm influencing system and supported on said seat, a ring of sound damping material between said seat and the peripheral portion of said diaphragm and against which the latter bears, and spring means having a plurality of yielding bearing points, said spring

means being arranged between and bearing against said outer abutment and the peripheral portion of said diaphragm and adapted to hold said diaphragm in a yielding manner against said seat.

3. A telephonic receiver comprising a casing provided with inner and outer substantially rigid abutments, an electro-magnetic diaphragm influencing system arranged within said casing, a diaphragm extending over said diaphragm influencing system and having its outer periphery supportingly seated on said inner abutment, and means embodying a plurality of spring devices arranged between the said outer abutment and the peripheral portion of said diaphragm and adapted to hold said diaphragm in a yielding manner against said inner abutment.

4. A telephonic receiver comprising a casing provided with an annular seat and at a distance therefrom with an abutment, an electro-magnetic diaphragm influencing system within said casing, a diaphragm extending over said diaphragm influencing system and supported at its periphery by said seat, a bearing ring and a plurality of spring fingers arranged between said abutment and the peripheral portion of said diaphragm and adapted to exert a yielding pressure on said diaphragm.

5. A telephonic receiver comprising a casing provided with an annular seat and at a distance therefrom with an abutment, an electro-magnetic diaphragm influencing system within said casing, a diaphragm extending over said diaphragm influencing system, and supported at its periphery by said seat and a bearing ring having a plurality of spring fingers integral therewith arranged between said abutment and the periphery of said diaphragm and adapted to exert a yielding pressure against the latter.

6. A telephonic receiver comprising a casing provided with an annular seat and at a distance therefrom with an abutment, an electro-magnetic diaphragm influencing system within said casing, a diaphragm extending over said diaphragm influencing system and supported at its periphery by said seat, a ring of sound damping material arranged between said seat and the peripheral portion of said diaphragm and a bearing ring provided with a plurality of spring fingers arranged between said abutment and the peripheral portion of said diaphragm, said fingers being arranged to bear at a plurality of points against said diaphragm.

7. A telephonic receiver comprising a casing provided with an annular seat and at a distance therefrom with an abutment, an electro-magnetic diaphragm influencing system within said casing, a diaphragm extending over said diaphragm influencing system and supported at its periphery by said seat,

4
a ring of soft damping material arranged between said seat and the peripheral portion of said diaphragm, a bearing ring provided with a plurality of spring fingers arranged 5 between said abutment and peripheral portion of said diaphragm, said fingers being adapted to bear against the latter at a plurality of points, and sound damping means arranged between the tips of said fingers and 10 the peripheral portion of said diaphragm.

8. A telephonic receiver comprising a casing provided with an annular seat and at a distance therefrom with an abutment, an electro-magnetic diaphragm influencing system 15 within said casing, a diaphragm extending over said diaphragm influencing system

and supported at its periphery by said seat, a ring of soft sound damping material arranged between said seat and the peripheral portion of said diaphragm, a bearing ring 20 provided with a plurality of spring fingers arranged between said abutment and the peripheral portion of said diaphragm, said fingers being arranged to exert a yielding pressure against said diaphragm and a ring 25 of soft sound damping material arranged between the diaphragm and the tips of said fingers.

Signed at London, England, this sixteenth day of May, 1924.

EDWARD ALFRED GRAHAM.
